UNITED STATES PATENT OFFICE.

CHARLES DOERING, JR., OF CHICAGO, ILLINOIS, ASSIGNOR TO ADAMS & ELTING CO., OF CHICAGO, ILLINOIS, A CORPORATION OF ILLINOIS.

APPARATUS FOR COATING ARTICLES WITH PULVERULENT MATERIAL.

976,445.

Specification of Letters Patent. Patented Nov. 22, 1910.

Application filed September 6, 1910. Serial No. 580,647.

To all whom it may concern:

Be it known that I, CHARLES DOERING, Jr., citizen of the United States, residing at Chicago, in the county of Cook and State of Illinois, have invented certain new and useful Improvements in Apparatus for Coating Articles with Pulverulent Material; and I do hereby declare the following to be a full, clear, and exact description of the invention, 10 such as will enable others skilled in the art to which it appertains to make and use the same.

This invention relates to improvements in apparatus for applying bronze powder or similar pulverized dry color to articles of all kinds, such as, furniture, fixtures, hardware, etc., the object being to provide apparatus which will uniformly coat such articles with such pulverized dry color rapidly, efficiently 20 and economically, and consists in the features of construction and combinations of parts hereinafter fully described and claimed.

In the accompanying drawings illustrating a suitable embodiment of the invention: Figure —1— is a view in central vertical longitudinal section of an apparatus constructed in accordance with my invention. Fig. —2— is a vertical transverse section of 30 the same on the line 2—2 of Fig. —1—. Fig. —3— is a top plan view of the same. Fig. —4— is a fragmentary detail vertical section on the line 4—4 of Fig. —1— showing the dry color container pivotally mounted upon one of the doors of the apparatus. Figs. —5— and —6— are views in side elevation of respectively opposite sides of latches employed for maintaining the doors locked. Fig. —7— is a detail horizontal 40 section on the line 7—7 of Fig. —5— showing the latch in its engaged position. Fig. —8— is a horizontal section of the apparatus. Fig. —9— is a detail view showing the window-frames employed at the sight holes.

In bronzing articles such as metallic bedsteads, window guards, hardware, and the like it has been customary to mix the bronze powder, or other dry color used, with so-called bronze-size, a quick-drying adhesive liquid, and applying the mixture to the article by means of a brush.

Recently it has been attempted to apply the bronze powder in its dry state to the still moist, sticky, size-covered surface of the article to be bronzed by means of an air blast

conveying such powder, the latter adhering to the moist surface upon coming in contact therewith. This method has been found to be far cheaper and more efficient than the older method of applying the bronze-containing size by means of a brush.

Applying bronze powder and the like to moist surfaces by means of an air current carrying the powder has for many years been practiced by printers and in some instances by manufacturers of other articles but while cheaper from the labor saving standpoint, this method occasioned waste of the bronze powder which is very expensive, and in some instances was abandoned for that reason.

In applying the powder it is obviously essential that the same should be uniformly applied to every part of the sized surface so as to apply to the latter as many particles of the same as it is capable of holding but at the same time to prevent any excess of the powder from remaining deposited upon the surface at any point to be subsequently removed with the article from the apparatus and then brushed from the surface or otherwise removed, as it is thereby wasted. The economy and efficiency of this method of bronzing is also largely dependent upon the rapidity with which the powder is applied to the sized surface. As previously stated the size-liquid dries very rapidly and, therefore, the bronze powder must be applied before the size becomes too dry and loses its adhesive power and, on the other hand, the powder cannot be applied while the size is still very moist. The exact time of application of the bronze powder is determined by the touch of the operator upon the sized surface. Obviously the air current constituting the vehicle for conveying the powder promotes rapid drying and this must also be taken into account by the operator. Hence, the rapidity of application of the powder is an important factor.

The powder used is usually impalpable and, hence, is very easily suspended in and conveyed by an air current, and after being agitated and suspended in the air time is required for it to settle to rid the air thereof. In settling it will obviously lodge upon all horizontal or substantially horizontal surfaces, the excess so deposited being wasted. As the apparatus cannot be opened for re-

moval of the bronzed article until the suspended powder has settled, a great deal of time is necessarily lost after each bronzing operation, depending upon the specific gravity of the powder being used. It is desirable also that a change from the use of a powder of one color to that of another color be quickly and thoroughly effected so the commingling of powders of different colors 10 may be avoided. It is further desirable to confine the collection of the powder after each operation to a particular place in the apparatus instead of permitting it to settle upon the bottom or other exposed supporting surfaces thereof. It is further desirable that the powder be fed to the apparatus in small quantities at frequent intervals rather than in large quantities as the use of large quantities at a time occasions waste 15 and lack of uniformity in the product. A further essential requisite to successful bronzing is to cause the air current carrying the bronze powder to impinge with equal force upon every point in the surface 20 of the article to be bronzed and into every crevice and corner of the same so that the particles of powder are thrown violently into contact with the sized surface and become embedded therein as deeply as possible. 25

My invention is designed to accomplish all of the foregoing objects and advantages, that is, first: to provide an apparatus in which the air currents carrying the bronze powder are caused to impinge with equal force upon every point in the surface and into every corner and crevice of the article. Second: to provide an apparatus in which the atmosphere is rapidly and efficiently 30 cleared of unapplied bronze powder and collected in a given part, whereby the operation of the apparatus is rendered more rapid, and whereby, furthermore, a change from the use of powder of one color to a powder of another color may be very quickly and efficiently effected. Third: to provide an apparatus in which very limited quantities of powder may be efficiently employed. Fourth: to provide an apparatus so organized as to occupy minimum space and in which only the air contained in the bronzing chamber proper is employed as the vehicle for conveying the bronze powder. 35

Other objects and advantages of the apparatus embodying my invention will appear in the following:

The apparatus comprises a rectangular chamber 1 open at opposite ends and equipped with doors 2 and 3 respectively, at said open ends, the latter being accurately fitted to said ends and suitably equipped to effectually seal the chamber when closed and locked. The upper part of the chamber 1 above the level of the upper walls of the openings therein constitutes a hood 4. The

side walls of said hood 4 preferably converge slightly so as to contract the upper part thereof. Said hood 4 is provided at either end with an opening 5 and 6 respectively, bordered by flanges 7 and 8 projecting from the upper wall of said hood. In 70 passages formed by said respective flanges 7 and 8 dampers 9 and 10 respectively, are disposed, the latter being preferably geared together by means, for example, of the sprocket wheels 11 and sprocket chain 12, the latter being connected at one point with one end of a lever 13 pivotally mounted between its ends upon a side wall of the chamber 1, said dampers being adapted to 80 be opened and closed in unison.

Fitting telescopically over the flange 7 is a tubular member 14 provided in its top wall with a flanged opening 15 over which several layers 16 of fabric are drawn so as 85 to enable air to pass therethrough but filtering from said air any dust or powder carried thereby. The flange 8 communicates with a dust collector 17 of any suitable construction, the hollow stem or inlet tube of 90 which telescopically receives said flange thus enabling said dust collector to be readily removed and replaced. Spanning said hood laterally at its lower end is a cross bar 18 disposed midway between the ends of said 95 hood, and substantially midway between said cross-bar 18 and the respective ends of said hood are two cross-bars 19 and 20 respectively. To each of the latter there is secured a foot bearing 21 of any suitable 100 construction. Journaled at their lower ends in said bearings 21 and between their ends in bearings 22 in the upper wall of said hood are vertical shafts 23 and 24, each equipped above said hood with a pulley 25. A belt 26 is trained over said pulleys 25 to cause said shafts to rotate in unison. The shaft 24 is further equipped with a pulley 27 or other adequate means for connecting the same 105 with a source of power. Upon each of said shafts 23 and 24 there is mounted a plurality of fan-blades 28 and 29 respectively, the said blades 28 being inclined oppositely to the inclination or cant of the blades 29 so that the latter will impart movement to the air 110 in the opposite direction from the blades 28. Suspended from said cross-bars 19 and 20 are parallel rails 30 connected adjacent their ends and at points between their ends by cross-bars 31 serving to reinforce the same 115 and maintain them parallel with each other. Beyond the respective ends of the apparatus are pairs of standards 32 to which pairs of rails 33 similarly cross braced are pivotally secured at one end. The other ends of 120 said rails 33 are equipped with hooks 34 adapted to engage the cross-bars 31 adjacent the ends of the rails 30 to support said rails 33 at one end upon the latter and serving also to prevent relative lateral or longitudi- 125 130

nal movement of said rails 30 and 33 respectively. Said connection is intended only to illustrate a suitable manner of rendering continuous through and beyond the ends of 5 the chamber 1 when open, the rails upon which trucks or cranes 34^a travel from which the articles to be treated are adapted to be suspended, it being obviously necessary to remove said rails from the paths of the 10 doors 2 and 3 when closing the latter.

Adjacent the floor of the chamber 1 and supported upon rods 35 passing through the side walls thereof is a pair of rails 36 which are also adapted to be suitably connected 15 with rails disposed externally of the apparatus and upon which trucks 37 are adapted to travel, the latter being adapted to support articles to be treated. In the instance illustrated the truck 37 is equipped with 20 pins 38 adapted to enter the caster-shank openings in legs of bedstead ends thus serving to exclude the powder from said openings and at the same time obviating the uncovered areas caused by contact of the suspension hooks employed to suspend articles from the trucks or cranes 34 and which must be subsequently bronzed by hand.

The structure is suitably reinforced externally in any suitable manner to render it 25 stable and durable. The openings in the ends of the chamber 1 are bordered by angle irons disposed so that one flange of each projects outwardly from said openings. The doors are similarly equipped with angle 30 irons on their edges, so as to provide snugly interfitting and overlapping frames suitably hinged together along one edge. Adjacent the other edges of the door frames latches 39 are pivotally secured, each of the latter 35 comprising a lever provided between its ends with an overturned flange 40 between the free edge portion of which and the opposing portion of the lever a substantially U-shaped recess is formed, the latter being preferably 40 flared slightly at its mouth portion. In said recess the contiguous edge portions of the door and door frame is received and by virtue of the contraction of said recess in its deepest part, the walls of the latter serve to 45 force the parts received therebetween together as said lever is turned to the limit of its movement in one direction. The latch shown and described is very simple and efficient as is also the construction of the doors 50 and door frames but these specific features of construction are merely exemplary of what is suited to my purposes and may be changed and varied as desired.

Upon the inner face of the door 2 there is 55 pivotally mounted a shelf 40^a equipped at its pivoted end with a pocket 41 the top wall of which is inclined relatively to the bottom wall thereof, the planes of said respective walls meeting in the free edge of the bottom wall. The side walls of said pocket 41

are continued to the free edge of the bottom wall thereof and constitute side edge flanges for the latter. The upper edges of said side flanges are disposed in the plane of said top wall so that when said shelf is turned on its 70 pivot to the upper limit of its movement the upper edges of said side flanges and the free edge of the bottom wall will contact with the inner face of the door, the latter serving thus to seal said pocket. On the lower face 75 of the bottom wall of said pocket I provide a wedge shaped projection 42 which is adapted to be engaged by the spiral projection 43 at one end of a shaft 44 journaled in a bearing in the door 2 and equipped at 80 its other end with a suitable handle for operating the same, said pocket 41 being thus adapted to be sealed whenever desired and the feed of powder to the air currents controlled by the operator.

In the side walls of the chamber 1, I provide suitable openings 45 covered preferably by glass or other transparent material, the latter being preferably mounted in frames 46 hinged to said side walls adjacent said 90 openings and adapted to be swung to seal the same and suitably maintained closed during the operation of the apparatus. Through said openings light is admitted and the operator is enabled to watch the progress 95 of the bronzing operation. Obviously any suitable means for illuminating the interior of the apparatus may be provided.

The operation of my said apparatus is as follows: One of said doors 2 or 3 having 100 been opened the article to be treated, which may be suspended from the truck or crane 34^a or may be mounted upon the truck, is inserted into the chamber 1 and after placing the dry color powder upon the shelf said 105 door is closed as are also the dampers and the frames containing the glass to cover the side holes so as to relatively effectually seal said chamber 1. The fans in the hood of the latter are then set in motion. The said 110 fans are preferably so disposed as to impart movement to the air in respectively opposite directions and are operated at high speed in order to agitate the air contained in the chamber 1 very violently. The rotation of 115 said fans to impart movement to the air in opposite directions produces mainly a rotary movement of the air in said chamber but by reason of the relatively small volume of space occupied and the extremely rapid movement 120 of the air upon various surfaces will cause deflection of the main current and an impingement of the latter upon every portion of the surface to be treated from practically all directions. The violent agitation of the air 125 will cause the latter to pick up the dry color powder from the shelf and will carry it in a cloud completely enveloping the article to be treated and will throw the colored particles 130 violently against the surface of said article

- to which said particles will adhere. The violent impingement of said particles upon said surface which is still plastic will cause said particles to become more or less embedded 5 therein but after said still plastic surface has been completely covered with said powdered particles it will obviously be impossible for further particles to lodge upon said surfaces. Thus the surface of the article will be completely coated with as much of the dry powder as will adhere to the same but no superfluous powder will remain deposited upon such surfaces.
- 10 The operator can by looking through the several sight holes watch the progress of the work and when he observes that the article is completely coated and ready to be removed he operates the lever 13 to open the dampers, the fans being still maintained in operation.
- 15 It is well-known that solids carried in suspension in fluids will always seek escape from the moving fluid to that which is less in motion or at rest. Accordingly, as soon as said dampers are opened the dust will 20 gather where the motion of the air is least. This will be in the dust collector into which the air gradually passes but by reason of the small volume of air contained in the apparatus its passage through said dust collector 25 and the deposit of the dry powder in the latter occupies exceedingly little time so that within a few seconds after opening said dampers the operator shuts off the transmission of power to the fans and by the time the latter are at rest the atmosphere within the 30 chamber will be clear of the powder.
- 35 It will be particularly noted that in my said apparatus only that air which is contained within the chamber at the time of introduction of the article to be coated is maintained violently agitated. This violent agitation and the friction caused by the contact of the air with the surface upon which it impinges causes the latter to become warm 40 very rapidly so that even during the very short interval required to coat the surface of the article to be treated the contained air will have increased considerably in temperature. The temperature is, of course, highest 45 at the time of completion of the coating operation and the higher temperature coupled with the motion of the air will obviously assist materially in drying the coating or sizing on the article so that when the latter leaves the apparatus it is almost sufficiently dry to be handled without danger of removing any considerable portion of the coating or otherwise injuring the appearance of the coated surface.
- 50 It is preferable for the economic operation 55 of the device that the article to be coated shall be delivered into the machine at one end and removed therefrom at the other end to be further treated as desired. For this purpose the several pairs of rails within the

apparatus may be made continuous with rails extending in both directions from the same.

While I have shown the dust collector mounted upon the hood and communicating with the latter, it will be understood that it may be located at any other convenient point. The dry powder carried by the air will be deposited wherever the motion of the air is insufficient to overcome gravity but during the period that the powder is being deposited upon the article it is desirable to prevent deposit of same at any point in the chamber. By merely opening the damper controlling communication with the dust collector the powder quickly finds its way into and becomes deposited in the latter but this action is hastened by opening both dampers so as to admit air at one point and discharge it through said dust collector.

During the time that the unapplied powder is deposited in the dust collector, the continuation of the violent motion of the air within the chamber and around the articles contained therein not only prevents any excess from becoming deposited on the latter but serves to blow from the surface thereof any particles not firmly adhering thereto.

A peculiarity of the operation of my apparatus is that the air currents within the same do not pick up all of the bronze powder contained on the shelf at once but take it up very gradually. Hence, as soon as the surfaces to be coated are fully covered by the powder, the operator turns the shaft to prevent any more powder being taken up and maintains the shelf sealed during the interval of dust collection.

While I have employed the term "bronzing" and have referred more particularly to "bronze powder" in the foregoing description it will be understood that said terms include any pulverulent material with which it may be desired to coat articles of any nature.

I claim as my invention:

1. A machine of the kind specified comprising a closed chamber adapted to receive articles to be coated, means for creating air currents in said chamber to impinge upon all portions of the surfaces of said articles, means for introducing coating material into said air currents for transmission to the surfaces to be coated, and means for clarifying the chamber of unapplied coating material after the article has been coated.

2. A machine of the kind specified comprising a closed chamber adapted to receive articles to be coated, means for creating air currents in said chamber to impinge upon all portions of the surfaces of said articles, means for introducing coating material into said air currents for transmission to the surfaces to be coated, and means for clarifying the chamber of unapplied coating material after the article has been coated and during circulation of air around the coated article.

3. A machine of the kind specified comprising a closed chamber adapted to receive articles to be coated, means for setting the air contained in said chamber in motion to impinge upon the surfaces of the articles to be coated, means for introducing coating material into said air for transmission thereby to the surfaces of said articles, and manually controlled means operable from the exterior of the casing for clarifying the chamber of unapplied coating material after the articles have been coated and during maintenance of air in motion within said chamber.
4. A machine of the class specified comprising a coating material supply, means for creating currents of air to take up the coating material in suspension and apply it to the article to be coated, means for closing the material supply to the air currents, and means for simultaneously removing the unapplied material from the air and the surplusage from the article after the latter has been coated.
5. A machine of the kind specified comprising a closed chamber adapted to receive articles to be coated, means for setting the air contained in said chamber in motion to impinge upon the surfaces to be coated, means for introducing coating material into said air, a dust collecting receptacle communicating with said chamber, and a damper controlling said communication, said damper when opened, permitting air from said chamber to enter said receptacle to deposit coating material therein during maintenance of circulation of air within said chamber, whereby the said chamber is freed of unapplied coating material after the article has been coated.
6. A machine of the kind specified comprising a closed chamber adapted to receive articles to be coated, a fan within the same adjacent one end for projecting air to impinge upon the bottom of said chamber, a fan disposed adjacent the other end and adapted to project air to impinge against the top of the said chamber, and a receptacle for coating material within said chamber, the bottom thereof being located to oppose the upward traveling air current, the air in motion being adapted to pick up coating material from said receptacle and apply it to the article.
7. A machine of the kind specified comprising a closed chamber adapted to receive articles to be coated, a fan within the same adjacent one end for projecting air to impinge upon the bottom of said chamber, a fan disposed adjacent the other end and adapted to project air to impinge against the top of the said chamber, a receptacle communicating with said chamber for collecting unapplied coating material from the said chamber after the article has been
- coated, and a damper controlling said communication.
8. A machine of the kind specified comprising a closed chamber adapted to receive articles to be coated, a fan within the same adjacent one end for projecting air to impinge upon the bottom of said chamber, a fan disposed adjacent the other end and adapted to project air to impinge against the top of the said chamber, a receptacle for coating material within said chamber, the bottom thereof being located to oppose the upward traveling air current, the air in motion being adapted to pick up coating material from said receptacle and apply it to the article, means operable from the exterior of the chamber for sealing said receptacle, a receptacle communicating with said chamber for collecting unapplied coating material therefrom after the article has been coated and while maintaining air in motion in said chamber, and a damper controlling said communication.
9. Apparatus of the kind specified comprising a closed chamber adapted to receive articles to be coated, an air inlet for said chamber, a dust collector communicating with said chamber, manually operated means controlling said air inlet to open or close the same, manually operated means controlling the communication of said dust collector with said chamber, a receptacle for coating material within said chamber, means operable from the exterior of said chamber for opening and closing said receptacle, and a plurality of devices adapted to be actuated to produce oppositely traveling air currents within said receptacle for conveying coating material to the contained articles.
10. Apparatus of the kind specified comprising a closed chamber adapted to receive articles to be coated, an air inlet for said chamber, a dust collector communicating with said chamber, manually operable means controlling said air inlet to open or close the same, manually operable means controlling the communication of said dust collector with said chamber connection between said manually operable means for actuating the same in unison, a receptacle for coating material within said chamber, means operable from the exterior of said chamber for opening and closing said receptacle, and a plurality of devices disposed within said chamber and adapted to be actuated to produce oppositely traveling air currents within said receptacle for conveying coating material to the contained articles.

In testimony whereof I have signed my name in presence of two subscribing witnesses.
